UNITED STATES PATENT OFFICE.

FORREST G. PURINTON, OF WATERBURY, CONNECTICUT, ASSIGNOR TO THE PATENT
BUTTON COMPANY, OF WATERBURY, CONNECTICUT, A CORPORATION OF CON-
NECTICUT.

SEAL OR TAG FOR MEATS.

Application filed July 13, 1925. Serial No. 43,236.

To all whom it may concern:

Be it known that I, FORREST G. PURINTON, a citizen of the United States, residing at Waterbury, in the county of New Haven and State of Connecticut, have invented 5 certain new and useful Improvements in Seals or Tags for Meats, of which the following is a specification.

My invention relates to new and useful 10 improvements in tags or seals for meat or fowls and is especially adaptable for smoke meats such as hams, sides of bacon, etc.

For articles of this nature, it is desirable 15 to produce a tag or seal having thereon a trademark or other insignia denoting the brand or the name of the producer.

One of the objects of the present invention is to produce a seal or tag which may be passed through meat, such as a ham, and 20 after the tag or seal is once applied, cannot be removed without so damaging the seal that the same cannot be re-used on some other article.

The present invention is a companion application to an application filed by me on 25 May 26, 1925, Serial No. 32,934, and one filed of even date herewith Serial Number 43,237.

The present application, however, contemplates the formation of a seal which may 30 be easily packed in bulk, it comprising but two parts which are assembled on the ham or other article when the same is tagged. By forming the article of two separate parts 35 secured at the time of tagging, there is no assembling cost for the manufacture which, from a commercial standpoint, is of value. Furthermore, the articles may be more easily packed in bulk and occupy less space 40 than if assembled at the time of their manufacture.

With the above and other objects in view, which will be more fully set forth as the 45 specification proceeds, the invention consists in certain new and novel arrangements and combination of parts as will be hereinafter more fully described and pointed out in the claims.

Referring now to the drawings showing a 50 preferred embodiment of my invention, and a slightly modified form,

Fig. 1 is a view in elevation of a ham

showing a tag or seal applied at the upper end,

Fig. 2 is a fragmentary detailed sectional view showing the mode of operation of applying the seal, 55

Fig. 3 is a fragmentary detailed view showing the tag or seal in its attached form,

Fig. 4 is a perspective of the head of a 60 wrench for curling the end of the spindle of the tag,

Fig. 4^a shows the spindle after the same has been curled, 65

Fig. 5 shows the spindle with the monogram head, the little washer or plate of the tag and the awl for applying the tag to the article, 70

Fig. 6 is a fragmentary view showing a slightly modified form of plate for the tag, 75

Fig. 7 is a perspective view showing the modified form of tag or seal with the spindle passed therethrough, and

Fig. 8 is a slightly modified form of 75 wrench for curling the ends of the spindle.

Referring now more specifically to the several views, and to Figs. 1 to 5 in particular, there is shown a spindle or shank 1, which is preferably formed of a rod or wire of aluminum of very limited ductility so that although the end of the spindle may be curled as at 2 and shown in Fig. 4^a, if subsequently bent or the curled portion straightened, the same will at once fatigue and break or snap, thus of course shortening the length of the spindle, 80

The upper end of the spindle 1 is headed as at 3, the spindle and head simulating in appearance an ordinary nail, the lower end of the spindle, however, not necessarily being sharpened, 90

Inasmuch as the spindle is formed of aluminum, the head may be easily and readily impressed with a monogram or trademark or other insignia, by subjecting the same to proper dies, 95

As may be seen in Fig. 5, a small washer 5 is provided, which in the present instance also simulates in outline a small ham, and this small washer or plate being formed of aluminum, will not in any way contaminate any article with which it may be used. Substantially centrally of this plate 5 is the small depressed opening 6, through which 100

will be passed the spindle 1 and allow the head 3 to fit flush within the plate. If desired, this small plate may be provided with insignia or reading matter and might be 5 of any desired shape or contour.

The application of this tag or seal to the ham is a simple one, an awl 7 being provided for the reception of the spindle 1, the latter, of course, having first been passed 10 through the small plate 5. The awl 7 is then passed through the neck of the ham 8 as clearly shown in Fig. 2, after which the awl will be pulled therethrough, and the end of the spindle will then be curled as 15 at 2, as clearly shown in Fig. 3.

The head 9 of the wrench 10 is shown in Fig. 4, which may be provided with the nose 11, and the small lip 12, and by a turn or two of this wrench, the curl will be 20 formed, tightly drawing the plate 5 against the surface of the ham, and holding the seal as a whole in position.

The seal is preferably applied to the neck of the ham, or in other words, at its 25 shank, where the cross sectional dimension is the smallest, so that if the curl of the spindle should be maliciously cut or broken off, the spindle will be too short to be re-used on another similar article.

30 Furthermore, although other spindles might be used by someone to try to counterfeit or misbrand an article, the probabilities are that they would not go to the trouble to make dies with the monogram and 35 insignia to head and impress the spindle, and a plain spindle would be quickly detected by the merchant handling the goods or by a purchaser.

In the modified form as shown in Figs. 6 40 and 7, the plate 13 is illustrated as circular in outline rather than simulating the appearance of a ham, and has the downwardly extending flange 14 to be drawn into the skin of the ham when the spindle is tightly 45 attached. This plate 13 has the small opening 15 and is depressed similarly to the depression 6 formed in the plate 5. The spindle 16 in this modified form of seal is identical with the spindle 1.

50 As may be understood from Fig. 8, it may be desirable to use a wrench 10 having a nose 11^a which is triangular in shape so that the curl 2^a will also be triangular in shape. When a wrench of this description is used, 55 the sharp bending of the spindle will cause the metal of the curl to weaken and the angles of the nose may even bite or nick the metal at the several angles to further weaken the spindle at the place of bending.

60 It is thus possible to use a metal of higher ductility than where a round curl is made, and this at times is desirable due to the fact that it is difficult to purchase in the open market a metal of extremely low ductility.

65 From the foregoing it will be seen that I

have provided a seal or tag which is formed of two parts, a spindle and a plate, the spindle being formed of aluminum of very low ductility, headed and monogrammed, and, after the tag or seal is applied, the end of 70 the spindle will be curled and will break or snap should the curl subsequently be tampered with.

It will be seen that there is no assembling necessary in the manufacture of the tag or 75 seal, thereby cheapening the cost and at the same time the two parts may be conveniently packaged and occupy but a minimum space.

It will also be understood that where a 80 spindle of very limited ductility is used, ordinary nose pliers might be used for putting the curl at the end of the spindle instead of the special form of wrench shown in Fig. 4, but when the spindle is formed of wire of 85 higher ductility, it is desirable to use a wrench similar to the one shown in Fig. 8, or one that has sharp sides to nick or sharply bend the metal so that it will break if subsequently straightened. In other words, the 90 ductility of the spindle will determine whether a round curl is to be formed on the end of the spindle, or whether the end is to be sharply bent as shown in Fig. 8.

Furthermore, by heading and monogramming the top of the spindle, the use of unmonogrammed or non-marked spindles will 95 be quickly detected.

Many slight changes might be made without in any way departing from the spirit and scope of the invention. 100

Having thus described my invention, what I claim as new and desire to secure by Letters Patent is:—

1. A tag or seal for meats comprising a 105 spindle formed of metal of limited ductility, the said spindle being headed at its upper end, a small metal plate provided with an aperture for the reception of said spindle, the lower end of the spindle being curled after the seal is applied to pull the 110 metal plate tightly against the article sealed, and the ductility of the metal being such that if the curl is subsequently bent, it will break from the spindle.

2. A tag or seal for meats comprising a 115 spindle formed of metal of limited ductility, the said spindle being headed, a small metal plate provided with an aperture for the reception of said spindle, the lower 120 ends of the spindle being curled after the seal is applied to pull the metal plate into the article sealed and the ductility of the metal being such that any attempt to uncurl the end will snap the curl from the 125 spindle.

3. A tag or seal for meats comprising a 130 spindle formed of aluminum of limited ductility, the said spindle being headed at its upper end, a small plate provided with an aperture for the reception of said spindle

and the metal about the aperture depressed so that the head of the spindle will lie flush with the said plate, the lower end of the spindle adapted to be curled after the 5 spindle has been passed through the article to be sealed to tightly hold the plate in position, and the ductility of the metal being such that if the curl be subsequently bent, it will break from the spindle.

10 4. A tag or seal for meats comprising a spindle formed of metal of relatively low ductility, the said spindle being headed, a plate fanciful in outline provided with a depressed opening and the spindle adapted 15 to pass within said opening and the head to lie flush with the upper surface of the plate, the lower end of the spindle being bent after the spindle is passed through the article to be tagged to thus draw the 20 plate tightly against the article, and the ductility of the spindle being such that any subsequent uncurling will snap the curl from the spindle.

25 5. A tag or seal for meats comprising a spindle formed of metal of limited ductility, the said spindle being headed at its upper end, a small plate fanciful in outline provided with an aperture for the reception 30 of said spindle, the lower end of the spindle adapted to be curled after the spindle has

been passed through the article to be sealed to thus tightly hold the plate in position, and the ductility of the metal being such that a subsequent bending of the curl will break it from the spindle.

35 6. A tag or seal for meats comprising a spindle formed of metal of limited ductility, the said spindle being headed at its upper end, a small metal plate provided with an aperture for the reception of said 40 spindle, the lower end of the spindle being sharply bent upon itself to weaken the metal and to pull the metal plate tightly against the article sealed, and the ductility of the metal spindle being such that if the 45 bent portion is subsequently straightened, it will break from the spindle.

7. A tag or seal for meats comprising a spindle formed of metal of limited ductility, a plate for receiving the spindle, the 50 lower end of the spindle being sharply bent after the seal is applied to pull the metal plate tightly against the article sealed, and the angularly bending of the metal and its limited ductility causing the 55 lower end of the spindle to snap off if the same is subsequently bent.

In testimony whereof I affix my signature.

FORREST G. PURINTON.
